DESIGN FOR A THERMOMETER

Norris E. Flanner, Wyckoff, N. J.

Application January 14, 1937, Serial No. 67,047

Term of patent 3½ years

To all whom it may concern:

Be it known that I, Norris E. Flanner, a citizen of the United States and a resident of the county of Bergen, Wyckoff, New Jersey, with a post office address at Box 67, Wyckoff, in the county of Bergen, State of New Jersey, have invented a new, original, and ornamental Design for Thermometers, of which the following is a specification, reference being had to the accom-

panying drawing, forming part thereof:

In which

Figure 1 is a front elevational view of a thermometer showing my new design; and

Figure 2 is a side elevational view thereof.

I claim:

The ornamental design for a thermometer, as shown.

NORRIS E. FLANNER.
